UNITED STATES PATENT OFFICE.

OSCAR A. LANE, OF ADRIAN, MICHIGAN.

WRENCH AND ANALOGOUS ARTICLE.

No. 809,962.

Specification of Letters Patent.

Patented Jan. 16, 1906.

Application filed February 6, 1905. Serial No. 244,373.

To all whom it may concern:

Be it known that I, OSCAR A. LANE, a citizen of the United States, residing at Adrian, county of Lenawee, State of Michigan, have 5 invented a certain new and useful Improvement in Wrenches and Analogous Articles, of which the following is a specification, reference being had to the accompanying drawings, which form a part of this specification.

10 My invention has for its object certain new and useful improvements in wrenches, vises, and analogous articles; and it consists of the construction, combination, and arrangement of devices hereinafter described and claimed, 15 and illustrated in the accompanying drawings, in which—

Figure 1 is a view in elevation of a monkey-wrench. Fig. 2 is a view in side elevation of a pipe-wrench embodying the same principle 20 of invention. Fig. 3 is a view in side elevation, illustrating my invention as embodied in a pipe-cutter. Fig. 4 is a view in side elevation as applied to a vise. Fig. 5 is a view showing the sliding jaw in longitudinal section. Fig. 6 is a view in section on the line 25 6 6, Fig. 5. Fig. 7 shows a modification in the construction of the pipe-cutter.

The object of my invention more particularly is to provide a quick-acting wrench for 30 various purposes or a quick-acting vise, my invention being applicable to monkey-wrenches, pipe-wrenches, and pipe-cutters, vises, and similar articles of manufacture, the principal difference in various modifications of the invention consisting mainly in the different 35 forms of jaws.

I carry out my invention as follows:

In the drawings, *a* represents a shank provided with a fixed jaw *b*. The shank is shown 40 toothed upon the edge thereof opposite the fixed jaw, as indicated at *c*. A sliding jaw is indicated at *d*, provided with a sleeve surrounding the shank, so as to be moved back and forth upon said shank.

45 My invention contemplates as one of the chief features thereof the provision of a sliding dog *e*, preferably of rectangular form, toothed, as indicated at *f*, at one end thereof to engage the teeth upon the shank. The 50 toothed portion of the dog preferably projects within a portion of the sliding jaw, as shown. The sliding jaw, on the outside thereof, on which the dog is located, is cut away or constructed with an open recess adjacent to the 55 teeth of the shank to receive one end of the dog, and an operating-screw to engage the

dog is indicated at *g*. The screw has a threaded engagement with the dog, and preferably has both the extremities thereof engaged in the corresponding portions of the sleeve on either side of the head of the dog. The screw is preferably provided with a collar *h*, located in the recess of the sleeve to hold it in proper engagement with the sleeve and prevent its moving out from such engagement. In Figs. 65 1 and 2 the screw is shown provided with a milled head. In Fig. 3 the screw is more extended than in Figs. 1 and 2 and provided with a T-handle. In Fig. 4 the screw is shown also passed through the fixed jaw and provided with a handle-bar. The sliding jaw on the side opposite the toothed portion of the shank is chambered to receive a spring, (indicated at *i*.) The orifice through the sleeve of the sliding jaw, through which the shank 70 is extended, is made larger at the front end thereof than at the rear, so as to permit the front end of the jaw to tilt sufficiently to allow the teeth of the dog to be disengaged from the teeth of the shank. By pressing down 75 the rear end of the sliding jaw the teeth of the dog may thus be disengaged from the teeth of the shank, so that the sliding dog may readily be moved to and fro by simply a sliding movement and without manipulating the 80 screw engaging the dog. It will thus be seen that a very quick acting wrench is secured, whereby the sliding jaw can be quickly moved into engagement with a bur. Should a closer engagement be required, the screw may be 85 manipulated to close the sliding jaw more firmly upon the bur. It will readily be seen that without employing the adjusting-screw the sliding jaw can be moved upon the bur, 90 so that only an interval between two teeth of 95 the shank could in any event intervene, and if a finer adjustment were required a simple turn of the screw would effect any nicety of adjustment desired, but the main movement of the sliding jaw would be effected without the 100 adjusting-screw.

In Fig. 2 the jaws *b* and *d* are toothed, the same being preferably provided with removable toothed portions, (indicated at *j* and *k*.) In Fig. 3 the jaws *b* and *d* are shown provided 105 with cutters, (indicated at *l* and *m*.) In Fig. 4 the two jaws are shown provided with toothed jaws, (indicated at *n* and *p*.) said toothed jaws being preferably removable also. As applied to a vise the movable jaw is shown 110 also provided with means (indicated at *q*) whereby the device may be secured upon a

bench or suitable support. Evidently the principle of the invention is the same in all of the modifications shown.

It will be noticed that the toothed portion 5 of the dog projects within the forward head or portion of the sleeve. The forward portion of the orifice through the sleeve being larger at the lower forward portion thereof, as indicated at *r*, permits, as above observed, 10 the tilting of the sliding jaw to disengage the dog from the shank, while at the same time when strain is applied to the wrench it embeds the teeth of the dog into the teeth of the shank, and the strain is longitudinally of the 15 face of the sliding jaw or at right angles to the shank, so that there is no danger of stripping the teeth or marring them in operation. The spring *i* serves to throw the forward end of the sliding jaw in such a manner as to hold 20 the dog in engagement with the shank.

As applied to a pipe-cutter the fixed jaw *b* may be provided with one or more cutters *l*, two being shown in Fig. 7.

On account of the orifice in the sleeve being enlarged at the end thereof adjacent to the 25 fixed jaw and on the side of the fixed jaw, it will readily be seen that the sliding jaw may be tilted by pressure upon the rear end of the screw *g* in a direction toward the shank. This 30 is a matter of particular convenience and utility, as the rear end of the operating-screw is in position to be easily and readily manipulated, while the length of the screw also affords considerable leverage to secure the tilting 35 of the jaw.

What I claim as my invention is—

1. In an implement of the nature described the combination of a shank provided with a 40 fixed jaw and toothed upon the side thereof opposite said jaw, a sliding jaw provided with a sleeve passing entirely around said shank and movable longitudinally thereupon, and constructed with an open recess on the outside thereof forming two shoulders adjacent 45 to the teeth of the shank, a dog engaged with said sleeve to engage the teeth of the shank having an arm extending into said recess, and a screw to engage said arm and the adjacent shoulders of the sleeve, the sleeve of the sliding 50 jaw cut away on the side of the fixed jaw forming a wedge-shaped chamber to permit the sliding jaw to tilt upon the shank to permit the disengagement of the dog from the shank, and a free movement of the sliding 55 jaw longitudinally upon the shank, the sliding jaw arranged to be tilted toward the fixed jaw by pressing the rear end of said screw toward said shank.

2. In an implement of the nature described 60 the combination of a shank provided with a

fixed jaw and toothed upon the side thereof opposite said jaw, a sliding jaw provided with a sleeve surrounding said shank and movable longitudinally thereupon and constructed with an open recess on the outer side thereof adjacent to the teeth of the shank, said sleeve provided with an orifice enlarged at the end thereof toward the fixed jaw and on the side of the fixed jaw, to permit the tilting of the sliding jaw, a dog engaged with said sleeve on the side thereof opposite the sliding jaw to engage the shank, a screw to engage the dog, and a spring within said orifice of the sleeve to hold the dog in normal engagement with the shank, whereby the dog may be lifted out of engagement with the shank by tilting the sliding jaw and moved longitudinally thereof substantially as set forth, the sliding jaw arranged to be tilted toward the fixed jaw by pressing the rear end of said screw toward the shank.

3. In an implement of the nature described, the combination of a shank provided with a fixed jaw and toothed on the side thereof opposite the jaw, a sliding jaw provided with a 85 sleeve mounted on said shank and constructed with an open recess on the outer side thereof adjacent to the teeth of the shank and arranged to permit the tilting of the front end of the jaw upon the shank, a dog of rectangular form 90 engaged within the recess of said sleeve, said dog having a toothed portion at its forward end projecting under the forward end of the sleeve, and a screw to engage the opposite end of the dog, said dog movable with the 95 tilting of the jaw, the sliding jaw arranged to be tilted toward the fixed jaw by pressing the rear end of said screw toward the shank.

4. In an implement of the nature described the combination of a shank provided with a fixed jaw and toothed upon the side thereof opposite said jaw, a sliding jaw provided with a sleeve surrounding said shank and movable longitudinally thereupon, a dog engaged with said sleeve on the side thereof opposite the 105 sliding jaw to engage the teeth of the shank, and a screw to engage the dog, the sleeve of the sliding jaw constructed to tilt upon the shank to permit the disengagement of the dog from the shank, and the free movement of the sliding 110 jaw longitudinally upon the shank, said screw passing through the fixed jaw.

In testimony whereof I have signed this specification in the presence of two subscribing witnesses.

OSCAR A. LANE.
